**ELECTRON DISCHARGE DEVICE ANODE FIN HAVING
HEAT DISTORTION PREVENTIVE MEANS
INCORPORATED THEREIN**

BACKGROUND OF THE INVENTION

This invention relates to electron discharge devices and more particularly to internal anode fins utilized therein. Anode fins may be of single or plural, parallel construction and are employed to achieve desirable anode current characteristics in, for example, horizontal deflection amplifier tubes used in color television receivers. While this type of anode design provides this desirable control of anode current, the leading edges of the fins, which extend close to the cathode, are subject to very high current densities and consequently very high temperatures. The high temperatures cause the fin material to expand along the leading edge thereof. The repeated expansion and contraction that occurs during the operating life of the tube, for example, in a television receiver, causes the material to stretch, and the leading edge of the fin to become permanently deformed. This deformation may appear as a side-to-side rippled effect along the edge or may even produce a twisting action which exposes the side of the fin to the cathode of the tube.

When this occurs the tube characteristics are adversely affected. For example, the anode or plate current decreases, and the screen grid current increases, thus decreasing the plate to screen current ratio. The inefficient operation that results therefrom further raises tube temperatures and makes the tube susceptible to control grid and screen grid emission and their associated problems. This chain of events has a detrimental effect on overall tube performance, reliability, and life expectancy. In a television receiver, these effects are manifested in a decrease in the width of the scan and a reduction in the high voltage to the picture tube. If the fin distortion becomes severe enough, it may cause the fin to short out to either the beam plate or the screen grid, thus rendering the tube inoperative.

OBJECTS AND SUMMARY OF THE INVENTION

It is, therefore, an object of the invention to obviate the disadvantages of the prior art devices.

It is a further object of the invention to enhance the operating characteristics of tubes employing anode fins.

It is yet another object of the invention to provide a more durable anode fin.

Other objects of the invention are to increase the life expectancy and stability of operating characteristics of tubes employing anode fins.

These objects are accomplished in one aspect of the invention by the provision of an anode fin having heat distortion preventive means incorporated therein.

BRIEF DESCRIPTION OF THE DRAWINGS

FIG. 1 is a sectional plan view of a typical electron discharge device utilizing the invention;

FIG. 2 is a partial plan view of an alternate form of the invention;

FIG. 3 is an elevational sectional view of a specific embodiment of the invention incorporated in a plate fin taken along the line 3-3 of FIG. 2;

FIG. 4 is an elevational view of another embodiment of the invention taken along a line similar to FIG. 3; and

FIG. 5 is a partial perspective view of a plate fin incorporating the invention.

DESCRIPTION OF THE PREFERRED EMBODIMENTS

For a better understanding of the present invention, together with other and further objects, advantages and capabilities thereof, reference is made to the following disclosure and appended claims in connection with the above-described drawings.

Referring now to the invention with greater particularity, in FIG. 1 there is shown an electron discharge device 10 of a type known as a beam power tube and used, for example, as a horizontal deflection amplifier in television receivers. The device 10 is comprised of a glass envelope 12 and an electrode cage 14 which is positioned between a pair of supporting micas 16, only one of which is shown.

The electrode cage comprises a cathode 18 having an electron emissive material 20 thereon, a control grid 22, a screen grid 24, a beam-confining plate 26, and an anode 28 having an anode fin 30 projecting inwardly of the cage toward the cathode. If desired, heat-radiating wings 32 may be attached to the fin 30 or to some other suitable location on the anode 28.

15 The anode or plate 28 is comprised of halves 34 and 36 having, respectively, end walls 38 and 40. Oppositely disposed sidewalls 42 and 44 project from end wall 38 and are formed to provide outwardly extending longitudinal joining flanges 46 and 48 at the portion thereof remote from end wall 38.

20 Likewise, oppositely disposed sidewalls 50 and 52 project from end wall 40 and are formed to provide outwardly extending longitudinal joining flanges 54 and 56 at the portion thereof remote from end wall 40. Anode fins 30 are fixedly positioned between pairs of the joining flanges so that their leading edges 58 project inwardly toward the cathode. The fins 30 may be comprised of a substantially U-shaped, double thickness of material, as shown in FIG. 1, as two spaced-apart, parallel members of single thickness, as shown in FIG. 2, or as 25 a single thickness of material. The invention disclosed herein 30 is equally adaptable to any of the above-described fin designs.

35 The anode 28 and fins 30 for this type of tube are generally fabricated from high expansion alloys; i.e., alloys having a coefficient of expansion in the neighborhood of $20 \times 10^{-6}/^{\circ}\text{C}/\text{in}$. Thus, a plate fin 1.75 inches long would experience an expansion of .021 inches at 600°C . This, however, is true for a fin that is at a uniform temperature and that is free to expand in all directions without hindrance. In an operating tube, however, the plate fin has a very pronounced temperature gradient 40 along the leading edge and also from the edge back to the main portion of the plate. Furthermore, the back of the fin is staked tightly to the main plate structure and is not free to expand. It is these conditions that produce such severe deformation and buckling of the fins.

45 Another condition affecting the plate response to temperature change is the material from which the plate and fin are fabricated. Generally, this material is bimetallic; for example, copper-cored nickel or aluminum-coated steel. The unequal 50 temperature distribution over the surface of the fin together with the bimetallic effect of the dissimilar layers produces severe stresses in the fin. These stresses and the bimetallic effect cause the fin to bend in a sideways direction. After repeated heating and cooling with the consequent application of stress, the material crystallizes and becomes permanently 55 deformed and will not return to its original shape.

55 This condition is alleviated by this invention by providing the fins 30 with heat distortion preventive means 60, as may be seen in FIGS. 3, 4 and 5. The heat distortion preventive means 60, in the instant concept, take the form of expansion 60 openings 62. In FIG. 3 these openings 62 are configured as substantially V-shaped notches 64. They are three in number, substantially equally spaced-apart in the embodiment shown, but this number may vary depending upon the length of the fin.

65 In FIG. 4 the openings are provided in the form of rectangular slots 66, spaced as in the embodiment described above.

In FIG. 5 is shown the locking tabs 68 which lock the rear portion of the fins 30 to the flanges on the anode halves.

The expansion openings 62 in the leading edges of the fins 70 30 allow controlled expansion thereof during operation without undesirable stresses being applied and the consequent buckling thereof which was so detrimental to prior art devices.

75 For even further strengthening, either the fins 30 and the main portion of the anode 28 or both may be provided with laterally extending reinforcing beads 70. When both the fins

and anode are provided with the beads 70, they should be aligned, as is shown in FIG. 5. Also, the beads on the fins should be equally spaced between the expansion openings.

Thus, it will be seen that there is herein provided a new and novel electron discharge device having obvious advantages over the prior art. The heat distortion preventive means greatly enhance the operating characteristics of the device. The anode fin is far more durable than prior art fins and the device itself has an increased life expectancy with greater stability of operating characteristics over the life thereof.

While there have been shown and described what are at present considered the preferred embodiments of the invention, it will be obvious to those skilled in the art that various changes and modifications may be made therein without departing from the scope of the invention as defined by the appended claims.

We claim:

1. In an electron discharge device having a cathode and at

least one grid; an anode surrounding said cathode and said grid; and a fin formed to project inwardly of said anode to a point closer to said cathode than any part of said anode, the improvement comprising: heat distortion preventive means incorporated in said fin.

2. The device of claim 1 wherein said heat distortion preventive means comprises a plurality of expansion openings formed in the edge of said fin facing said cathode.

3. The device of claim 2 wherein said openings are configured as substantially V-shaped cutout areas.

4. The device of claim 2 wherein said expansion openings are substantially rectangular slots.

5. The device of claim 4 wherein said slots are three in number and are substantially equidistantly spaced along said edge of said fin.

6. The device of claim 2 wherein said expansion openings extend less than the width of said fin.
